SPARK PLUG HAVING SPARK INTENSIFYING DEVICE THEREIN

James D. Curtis, Collingswood, N. J., assignor, by mesne assignments, to Helen Baus Curtis, Camden, N. J.

Application January 28, 1932, Serial No. 589,372

3 Claims. (Cl. 123—169)

The subject of my invention is a spark plug for use with automobile or other internal combustion engines having a spark intensifying device therein whereby a greatly improved spark is secured.

In general my device consists of a spark plug consisting of a porcelain insulator having at one end thereof a terminal, a spring in contact with said terminal, an intensifying device comprising a plurality of elongated electric connecting elements mounted adjacent each other and adjacent the conducting elements of said spark intensifier, an inner electrode, a metallic shell surrounding said insulator and clamping it therein and a ground electrode on said shell cooperating with said inner electrode.

One feature of my invention is the spark intensifying device which consists of an insulating casing having an axial perforation therethrough, metallic caps covering the ends of said casing, and rollers extending laterally through said casing and through the perforation therein so that their ends are adjacent said caps and their central portions are adjacent each other.

Another feature of my invention is that the shell is provided with a baffle of smaller internal diameter than the remainder of the shell so that a higher compression area is created adjacent the electrodes which form the spark gap.

Yet another feature of my invention is the provision of a ground electrode which extends for a considerable distance parallel to the central electrode which forms the opposite side of the spark gap. The ground electrode is of full cross section throughout said parallel portion.

For a further exposition of my invention reference may be had to the annexed drawings and specification at the end whereof my invention will be specifically pointed out and claimed.

In the drawing,

Fig. A is a side elevation of my device.

Fig. B is a vertical cross section through my device, and

Fig. C is a lateral cross section on line C—C of Fig. A.

For the purposes of illustration in the drawing I have selected one embodiment which my invention may take. This embodiment consists of an electrode consisting of a terminal cap 1, and a threaded one piece terminal 2. The screw threads or other fastening means on terminal 2 cooperate with threads on one end of an insulator 3 which is preferably made of porcelain. The terminal 2 is preferably cemented at its

screw threads into insulator 3. Beneath terminal 2 is provided a spring 4 which is shown as consisting of a relatively flat dish-shaped element having four prongs. I may, however, substitute a spring of any other shape or any convenient conducting material, such as metallic wool.

Within a chamber in insulator 3 there is provided a spark intensifying device. This consists of a casing 6 of insulating material having an axial perforation or chamber 17 passing therethrough. At its opposite ends casing 6 carries metallic caps 5. Extending laterally through casing 6 and through the chamber 17 therein I provide rollers 7 of electric conducting material. Rollers 7 are mounted so that portions of their ends underlie portions of the caps 5 as is best seen from the lower roller 7 in Figure B. Rollers 7 are mounted in casing 6 so as to be adjacent to but out of contact with each other and so as to have exceedingly limited movement relative to each other and to casing 6. Rollers 7 are shown as disposed at an angle to each other but they may be located parallel to each other but spaced apart with an opening between them.

Insulator 3 has its intermediate portion enlarged on its outer surface. This enlargement is secured between a metallic gland nut 8 and the metallic shell 9 which has screw threaded or other adjustable attachment to gland nut 8. Between gland nut 8 and insulator 3 there is interposed a gasket 11 and between a shoulder of shell 9 and insulator 3 there is interposed another gasket 13. By screwing up gland nut 8 and shell 9 insulator 3 is clamped therein between gaskets 11 and 13.

Mounted in the lower part of the chamber within insulator 3 is an inner electrode 10 which has contact with the lower cap 5 of the spark intensifier. Gasket 12 is interposed between a shoulder of electrode 10 and insulator 3. From the lower portion of insulator 3 extends inner spark point 14 which contacts with the electrode 10 to form a part of the inner electrode.

Shell 9 forms the ground connection for the spark plug and has ground electrode 15 mounted at its inner end. Electrode 15 has a portion of full circular cross section extending opposite to inner electrode 14 so as to provide a spark gap of appreciable length between electrodes 14 and 15.

In its lower inner portion shell 9 has a baffle 16 of decreased diameter adjacent the spark gap between electrodes 14 and 15. This serves to

furnish an area of increased pressure adjacent to the spark gap so that the shock of the explosion does not enter the chamber between the shell and the insulator inside the baffle. This prevents cracking of the insulator at a point just beneath its point of contact with the shell.

I do not intend to be limited in the practice of my invention save as the scope of the prior art and of the attached claims may require.

10 I claim:

1. In a spark plug including in combination an insulator having a chamber therein, a terminal mounted in said chamber at one end of said insulator, and a spring having contact with said terminal, a spark intensifier including in combination, a casing forming a part of said spark intensifier in said chamber and having an axial perforation therethrough, metallic caps mounted on the ends of said casing and closing 15 the ends of said perforations, one of said caps being in contact with said spring, and elongated

rollers mounted in said casing laterally and passing through the perforation therein so as to partially underlie said caps at their outer ends and to be located in spaced relation in said perforation.

5

2. In a spark plug, a spark intensifying device comprising in combination, a casing of insulating material having an axial perforation therein, metallic caps overlying the perforated ends of said casing and overlying portions of the sides 10 of said casing, and metallic rollers mounted for limited movement in said casing and projecting through the perforation therein, portions of the ends of said rollers underlying portions of said caps and the central portions of said rollers 15 forming a spark gap within said casing between said rollers.

3. The combination according to claim 2 in which the axes of the rollers are at right angles as seen in plan.

20

JAMES D. CURTIS.
